LOCK CORE

Frank Ellison Best, Indianapolis, Ind.

Original application January 8, 1942, Serial No. 425,952. Divided and this application January 15, 1945, Serial No. 572,905

25 Claims. (Cl. 70—375)

1

Nature and objects

This is a divisional application of my co-pending application on Unpickable lock, filed January 8, 1942, Serial No. 425,952, now abandoned.

This invention relates to locks of the type provided with the lock-controlled assembly feature in which a primary lock mechanism, called a core, is adapted to be locked in a receptacle of a complementary lock mechanism of a secondary nature, called a housing, by key means.

This invention is directed to improvements in core means and the principal objects are to provide a core in which:

1. The core is of generally cylindrical form adapted to fit and function in a housing having a generally cylindrical receptacle.

2. The tumblers are of the flat ring type adapted to be compactly stacked, along with inter-spersed spacer rings, to form a cylindrical stack on the outside of a rear portion of said core, for easy manual assembly and disassembly particularly desired to facilitate the changing of the combinations thereof.

3. The tumblers are retained in operative position on said core by snap-ring means that can be easily removed and replaced in the manual re-combination of said core.

4. Said stack of ring tumblers alternately interspersed with spacer rings, surround keyway means, a locking bar, locking bar way means and groove means, the latter being adapted to accommodate lugs on the spacer rings to prevent their relative rotation about said core, said spacer rings being adapted to frictionally drive said tumblers at times and permit their sliding thereon at other times, forth and back, in arcuate paths, in the functioning of the said core.

Description of figures

I attain these and other objects by means disclosed in the accompanying drawings, in which:

Fig. 1 is a view in longitudinal section taken substantially on broken lines 1—1 of Figs. 2 to 17 inclusive showing a core constructed in accordance with my invention, said core being shown in its operative relation to a housing and having a key inserted therein in the position it would occupy preparatory to operating the said core.

Fig. 2 is a cross section taken on broken line 2—2 of Fig. 1.

Fig. 3 is a cross section taken on broken line 3—3 of Fig. 1.

Fig. 4 is a cross section taken on broken line 4—4 of Fig. 1.

2

Fig. 5 is a cross section taken on broken line 5—5 of Figs. 1, 18 and 22.

Fig. 6 is a cross section taken on broken lines 6—6 of Figs. 1, 18 and 22.

Fig. 7 is a cross section taken on broken lines 7—7 of Figs. 1, 18, 20, 21 and 22.

Fig. 8 is a cross section taken on broken lines 8—8 of Figs. 1, 18, 20, 21 and 22.

Fig. 9 is a cross section taken on broken lines 9—9 of Figs. 1, 18, 20, 21 and 22.

Fig. 10 is a cross section taken on broken lines 10—10 of Figs. 1, 18, 20, 21 and 22.

Fig. 11 is a cross section taken on broken lines 11—11 of Figs. 1, 18, 20 and 21.

Fig. 12 is a cross section taken on broken lines 12—12 of Figs. 1, 18, 20 and 21.

Fig. 13 is a cross section taken on broken lines 13—13 of Figs. 1, 18, 20 and 21.

Fig. 14 is a cross section taken on broken lines 14—14 of Fig. 1.

Fig. 15 is a cross section taken on broken line 15—15 of Fig. 1.

Fig. 16 is a cross section taken on broken line 16—16 of Fig. 1.

Fig. 17 is a sectional development taken on broken line 17—17 of Fig. 1 and on a smaller scale than the preceding figures, a portion of the face plate of the lock being omitted.

Fig. 18 is a fragmentary sectional development taken on broken lines 18—18 of Figs. 5, 6, 7, 8, 9, 10, 11, 12, 13, 14, 20 and 21.

Fig. 19 is a diagram illustrating the cycle of operation of the key in this core.

Fig. 20 is a fragmentary sectional development taken on broken line 20—20 of Figs. 7, 8, 9, 10, 11 and 18.

Fig. 21 is a fragmentary sectional development taken on broken line 21—21 of Figs. 7, 8, 9, 10, 11 and 18.

Fig. 22 is a fragmentary sectional development taken on broken line 22—22 of Figs. 5, 6, 7, 8, 9, 10 and 23.

Fig. 23 is a fragmentary sectional development taken on broken line 23—23 of Figs. 7, 8, 9, and 22.

Fig. 24 is an exploded isometric view showing a plurality of the operating parts of this lock core mechanism.

Fig. 25 is an exploded isometric view showing a key and a separable key bit in relatively separated relation.

Structural description Figs. 1 to 25

Figs. 1 to 25 inclusive disclose a lock comprising a lock housing, a core, illustrating this

invention, and a key adapted for cooperation with said core, said key having a combined portion, herein termed the key bit, that is detachable from the body portion of the key, herein termed the key blade. The primary lock mechanism shown to the right of the end plate 140, in Fig. 1, constitutes the core illustrating this invention, the skeleton of which is shown exploded in Fig. 24.

Figs. 1 to 17 inclusive show a cylindrical housing 40 that is open at the outer end and preferably has an integral or rigidly connected end wall 41, Figs. 1 and 17.

Preferably the housing 40 is internally provided adjacent the outer end with an annular shoulder 42, Figs. 1 and 17, for supporting a disc portion 68 of the face member 63 of the core, as herein-after described.

Five annular rows of inwardly projecting rigid lugs are provided in the housing 40 with the outermost or first annular row of lugs positioned near the open end of said housing and each succeeding annular row of lugs spaced from the preceding annular row longitudinally of the housing. These annular rows of lugs are best shown in the sectional development, Fig. 17.

The first row of lugs, shown at the right in Fig. 17, are numbered 43, 44, 45, 46 and 47 respectively; the second row of lugs are numbered 48, 49 and 50 respectively; the third row of lugs are numbered 51, 52, 53, 54, 55 and 56 respectively; the fourth row of lugs are numbered 57, 58 and 59 respectively; and the fifth row of lugs are numbered 60, 61 and 62 respectively. The functions of the lugs 43 to 62 inclusive are hereinafter fully described.

The skeleton of the core, Fig. 24, comprises a face member 63, a longitudinally movable bolt member 64, an inner body member 65, an outer body member 66 and a throw member 67. The numerals 63, 64, 65, 66 and 67 designate these members generally in Fig. 24. Said members are shown in exploded relation in Fig. 24 and in telescoped or assembled relation in Fig. 1. Each of said members is made up of a number of related parts or portions and the tumblers, which are preferably of ring-plate type, are assembled on the members 65 and 66 after these parts have been telescoped together, as hereinafter explained.

The face member 63 is preferably of one piece construction to provide great strength and offer great resistance to the application of force used for the purpose of destroying the core or gaining access through it.

This face member 63 comprises a disc portion 68 of large enough diameter to seat against the shoulder 42. The disc portion 68 is omitted in Fig. 17 to avoid confusion. An annular row of individually spaced apart outwardly protruding lugs 69, 70, 71, 72 and 73, see Figs. 1, 14, 17 and 24, are rigid with the face member 63 and spaced inwardly from the disc portion 68 a distance at least slightly more than the width of the housing lugs 43 to 47 so that they may be engaged back of the housing lugs 43 to 47 when the disc portion 68 rests against the shoulder 42 and is against or closely adjacent to the lugs 43 to 47 inclusive.

The face member 63 is provided, on the inner side, with a tubular sleeve 74 that is adapted to fit over a shank 75 on the end of the inner body member 65, see Figs. 1, 12, 13, 14, 15 and 24. Preferably the outer end of the shank 75 has a counterbore 76 therein, Fig. 24, that fits over a

cylindrical bearing portion 77, Fig. 15, which is formed within the sleeve 74, see also dotted lines, Fig. 1.

This counterbore 76 and bearing portion 77 help to provide a better bearing; and particularly cooperate to prevent the two side portions of the shank 75, which are separated by a keyway 78, from being pinched together. Dowel pins 79 in holes 218 secure the relatively telescopic sleeve 74 and shank 75 together, see Figs. 1, 12, 13 and 24, the holes for these dowel pins being shown in Fig. 24.

The keyway 78 extends through the face member 63 and inner body member 65 and is similarly numbered in these two parts. The cross sectional shape of this keyway may be varied to conform to the cross sectional shape of the keys to be used.

A portion 80 of the keyway is formed in the outer body member 66. This portion 80 is separately numbered and has inwardly projecting ribs 81 at the location where it intersects the lower curved surface of the outer body member 66, see Figs. 8, 9 and 24.

A key receiving notch 84 is provided in the end 25 of a tubular portion 82 of the throw member 67. A throw lug 83, having the curved cross sectional shape shown in Figs. 3, 4 and 24, is provided on the end portion of the throw member 67. The curvature of the throw lug 83 prevents the gear member 171-172 from being reversed or turned upside down in assembly.

A stepped portion 85 is provided on an end flange 86 of the inner body member 65 and around the base of the shank 75, see Figs. 24 and 11. The 35 inner end of the sleeve 74 abuts against this stepped portion 85 and plate 216 of the outer body member 66 when the members 66, 65, 64 and 63 are in assembled relation. The stepped portion 85 is shown in section in Fig. 11 and the end flange 86 is shown in elevation in Fig. 11 and in section in Fig. 10.

End flange 86 has a rear arcuate projection 387 that is rectangular in cross section adapted to form-fit rectangular arcuate groove 96 in circular end portion 92 of outer body member 66, Figures 9 and 24.

The inner member 65 has a tumbler-carrying portion 87 that is rigid with the end flange 86 and extends inwardly therefrom. The portion 87 is of the general cross section shape shown in Figs. 7, 8 and 9 throughout the major portion of its length.

Two-pronged shank 89 (of inner body member 65, Fig. 24), which is divided into prongs by keyway 78, protrudes from the inner end portion of the tumbler-carrying portion 87 and is adapted to telescope into two mating holes extending lengthwise through the tubular portion 82 of throw member 67.

The metal forming the juncture of these holes with the flat surface at their innermost end is rounded off slightly so that each prong of shank 89 may be peened, in assembly, to fill the cavity thus formed as at 219, Fig. 1, to thus secure the assembled parts in rigid integrality as by riveting.

A rib 90, see Figs. 1 and 5, is provided in the bottom of the tubular portion 82 to enter between the two parts of shank 89 for a short distance and support the two parts of shank 89 and the adjacent parts of the tumbler-carrying portion 87 against collapse or sidewise crushing pressures which might tend to relatively displace these parts. An integral pin 91 is provided on the 70 rib 90 for purposes hereinafter explained.

The outer body member 66, Fig. 24, has a circular end portion 92 that has a large opening 93 therethrough to receive the inner body member 65. A lug 94 projects outwardly from the end portion 92 and is notched on its under side to form a shoulder 95. A groove 96 is provided in the end portion 92 and extends under the lug 94. The function of parts 94, 95 and 96 are hereinafter explained in connection with the operation of key means.

The movable bolt member 64 comprises a crescent shaped end plate 97 that is provided with three lugs 98, 99 and 100 on its peripheral portion. The lugs 98, 99 and 100, see Figs. 13, 17 and 24, are adapted to cooperate with the set of fixed housing lugs 48, 49 and 50 and the set of fixed housing lugs 51, 52, 53, 54, 55 and 56 in controlling rotary movement of the members, as herein-after explained.

The end plate 97 has a number of relatively large and strong pins 101 protruding outwardly therefrom that are adapted to fit within holes 102 in the face member 63, see Figs. 1, 14, 15 and 24, when the bolt member 64 is in a position adjacent the face member 63 as shown in Fig. 1. I have shown three of said pins or lugs 101 and have shown them to be integral with the end plate 97.

The pins 101 form a very strong and rugged connection to resist torque and prevent said torque from being transmitted to the other parts of the lock in the event a screw driver or like instrument is inserted in the keyway 78 of the face member 63 and force applied to turn the same while the lugs 98, 99 and 100 are in engagement with the housing lugs 48, 49 and 50.

The end plate 97 of the bolt member 64 carries an inwardly protruding rigid bar extension 103 and an inwardly protruding rigid tube 104. The bar extension 103 and tube 104 telescope into a notch 105 and a bore 106 respectively in the inner body member 65 when the members are in assembled relation, see Figs. 1, 7, 8, 9, 10, 11 and 24. The tube 104 has a compression spring 107 therein. One end portion of the spring 107 seats in a recess 108, Fig. 1, in portion 68 of face member 63 and the other end portion of the spring 107 presses against the closed inner end portion of the tube 104. The spring 107 is thus caused to exert a yielding inward pressure on the movable bolt member 64 with the outer end portion of the spring abutting against the face member 63.

The bar extension 103, Figs. 7, 8, 9, 10, 11, 12, 18, 20, 21 and 24, is cut away on the right hand side, as respects the showing in Figs. 7 to 12, and 24, and carries an end piece 212 riveted thereto at 213, Fig. 18, to provide for the reception of a lock control bar 109. Parts 110 of the bar extension 103 and end piece 212 overhang the end portions of the lock control bar 109, see Figs. 18 and 24, for holding said lock control bar so that it may be moved transversely as respects the bar extension 103. Part 212 is riveted to bar extension 103 after members 64 and 65 are assembled.

The lock control bar 109 has inclined ribs 111 provided on the side thereof that is directed outwardly away from the bar extension 103 and the inclined ribs 111 are adapted to cooperate with inclined ribs 112 which are formed on the wall of the notch 105 in the inner body member 65, see Figs. 8, 18, and 20, so that when the bar extension 103 is moved longitudinally the lock control bar 109 will not only be moved longitudi-

nally therewith but will also be moved transversely of the bar extension 103.

Also it is to be noted that transverse movement of the lock control bar 109 controls the longitudinal movement of the bar extension 103 and bolt member 64. Due to the cooperation of the inclined ribs 111 and 112 the transverse movement of the lock control bar 109 will always be a parallel movement and said lock control bar 109 will not be tilted or inclined because it is firmly held by and between the inclined ribs 112 which are rigid with the portion 87 of the inner body member 65. The function of the lock control bar 109 which makes this parallel movement of said lock control bar 109 necessary is hereinafter described in connection with the mechanism with which it cooperates.

The end portion 92 of the outer body member 66 has three lugs 113, 114 and 115 on its peripheral portion as shown in Figs. 1, 9, 10, 17 and 24. The lugs 113, 114 and 115, Fig. 17, are positioned in an annular path between the set of housing lugs 51 to 56 inclusive and the set of housing lugs 57 to 59 inclusive. The lugs 113, 114, and 115 cooperate with housing lugs 51 to 56 inclusive and housing lugs 57, 58 and 59 to prevent endwise displacement of the outer body member 66 in the housing 40.

The outer body member 66 has a portion 116 extending inwardly from the end portion 92 and of a cross sectional shape as shown in Fig. 8. This body portion has an outwardly extending flange 117, shown at the left in Figs. 8 and 24, that is provided with two radial shoulders 118 and 119. Shoulder 118 engages with shoulder 128 of the portion 87 of the inner body member 65 while shoulder 119 engages with surfaces 150 of tumblers 146.

To the right of the shoulder 119 for a substantial distance, as respects the showing in Figs. 8 and 24, the portion 116 is cut away for a distance and then made wedge shaped to provide a key bit operating space 308, see Fig. 8, and to the right of this key bit operating space the portion 116 is of uniform thickness and finally this thicker portion terminates in a radial stop shoulder 120 positioned, preferably, diametrically opposite to the radial face or shoulder 118.

The portion 116 terminates at its inner end in a plate like portion 121 of substantially semi-circular shape, see Figs. 1, 7 and 24. This plate like portion 121 has a notch 209 to facilitate assembly of tumblers 146 which notch may be filled, after the tumblers are in place, by a form-fitting block 210, which, in common with plate like portion 121, has a groove 122 in the peripheral portion for the reception of a resilient lock ring 123 preferably of ring type, Figs. 1 and 7. The portion 87 of the inner body member 65 has a recess 124 to receive the inturned inner end portion 125 of the lock ring 123.

The portion 116 of the outer body member 66 has a longitudinally moving locking slide 130 provided therein, see Figs. 7, 8, 9, 22 and 23. The inner end portion 131 of the locking slide 130, shown at the left in Figs. 22 and 23, is of wedge shape and is adapted to lock into a wedge-shaped recess 132 in end plate 160, see Figs. 22 and 6. An overhanging plate portion 133 is provided on the locking slide 130 at one side of the inner end portion 131. The plate portion 133 overhangs the portion 131 and projects beyond the end of the same, as shown in Figs. 22 and 23. One edge 134 of the plate portion 133 is inclined and is positioned in engagement with a cam surface 135,

see Figs. 6 and 22, when the locking slide 130 occupies the position shown in Figs. 22 and 23. When the core is in operation the locking slide 130, will, at certain times, be moved to the right from the position shown in Figs. 22 and 23 so that the tip of the inner end portion 131 will follow a flat surface 136 and the tip of the plate portion 133 will follow a parallel flat surface 137, shown in Fig. 22.

The outer end of the locking slide 130 has a frusto-conical end portion 138, that is adapted to lock into a correspondingly shaped recess 139 in the end flange 86 under certain operating conditions hereinafter described.

The end plate 140, see Figs. 1 and 5, has three spaced lugs 141 on its periphery. The lugs 141 fit between the housing lugs 60, 61 and 62 and prevent rotation of the end plate 140 in the housing.

In addition to the cam surface 135 the end plate 140 has two other inclined cam surfaces 142, 143 on the side thereof adjacent the lock mechanism, see Figs. 1, 6, 7, 18 and 22. The flat surface 136 cooperates with the end portion of end piece 212 carried by the bar extension 103 to hold said bar extension 103 and the parts connected therewith in the position in which they are shown in Fig. 18, when the body members are in their initial or starting position. The end of end piece 212 carried by the bar extension 103 has a beveled surface 145 thereon for engagement with the inclined cam surfaces 142 and 143 as hereinafter described.

The cam surface 135 in cooperation with wedge shaped recess 132 and flat surface 137 controls endwise movement of the locking slide 130 to lock the outer body member 66 either to the end plate 140 or to the inner body member 65.

The cam surface 142, in cooperation with the lock control bar 109, governs longitudinal movement of the movable bolt member 64, Fig. 24, and thus cooperates in governing movement of the lugs 98, 99 and 100 into and out of the path of the housing lugs 48, 49 and 50, Fig. 17.

The cam surface 143 in cooperation with the lock control bar 109 governs movement of the bolt member 64 in moving the lugs 98, 99 and 100 into and out of alignment with the stop lugs 51 to 56 inclusive.

An inclined surface 144 is provided adjacent the cam surface 143 and the clearance space 38 of the end plate 140 is recessed to provide clearance for bar extension 103 and lock control bar 109 as hereinafter described.

The end plate 140 has a stop member 126 provided therein that is adapted to be engaged by a lug 127 which is rigid with and protrudes endwise from the inner body member 65 to limit the rotary movement of said inner body member 65 to substantially one hundred eighty degrees.

In assembling the elements of this lock core, most of which are shown in Fig. 24, it is advised to proceed as follows: with end piece 212 removed and lock control bar 109 in place, telescope members 64 and 65 and rivet 212 in place. Then with plate 216 and pins 217 removed and locking slide 130 in place, telescope members 64 and 65 into member 66 and rivet member 67 to the end of member 65. Then slide plate 216 sidewise into place and secure with pins 217. Lastly telescope sleeve 74 of member 63 over shank 75 of member 65 and pin with pins 79 in pin holes 218.

When these parts are telescoped together they constitute an uncombined core which forms a support of generally cylindrical shape for the

reception of a plurality of tumblers 146 and a plurality of tumbler spacers 147, both preferably of substantially ring shape. In Fig. 1 I have shown nine tumblers 146 and ten of the spacers 147. Obviously a greater or lesser number of tumblers and spacers may be used.

The tumblers 146 in the uncombined form are all of duplicate construction. A cross section, in a plane parallel with the flat sides of the tumbler, through one of these tumblers, after being combined by the insertion of notches 152 and 153 therein, is shown in Fig. 8. Each tumbler 146 has an inwardly protruding portion 148 that has a plurality of stepped shoulders 149 on one side thereof arranged and shaped so that they look like inverted stair steps when viewed from the position shown in Fig. 8.

Preferably the number of shoulders 149 correspond to one less than the number of increments in combining the tumblers of the lock core. In the present illustration, in Figs. 1 to 25 inclusive, I have shown nine of the shoulders 149. Hence ten increments are used in combining this lock, and the available combinations of the lock core 25 follow the formula of 10^n where n represents the number of tumblers of the core. Thus in a nine tumbler lock core of ten increments per tumbler, as shown, there are one billion combinations available.

30 The portion 148 of each tumbler has a surface 150 positioned opposite to the shoulders 149. This edge 150 is preferably straight and radial and is adapted to be engaged by the shoulder 119 of the flange 117 of the outer body member.

35 Each tumbler 146 is further provided, at a location approximately diametrically opposite from the stepped portion 148, with an inwardly extending widened portion 151 of substantial length, as shown in Fig. 8. Each widened portion 151 is provided with one or more relatively deep notches 152; and the widened portion 151 of at least one tumbler of each core is provided with a relatively shallow notch 153. Preferably several tumblers 146 of each lock core are provided with one or more of the shallow notches 153 for reasons hereinafter explained. The notches 152 and 153 are the combined portions of the tumblers and their positions in each instance are determined by the biting of the key and they are adapted 45 to receive the hereinbefore described lock control bar 109.

Obviously one or more dummy tumblers can be used, in a lock core, that are not provided with inwardly extending wider portions 151, where the 50 security of the lock is relatively unimportant.

The spacers 147 are of L-shaped cross section, as shown in Fig. 1, each of said spacers 147 having a flange 154 that extends over the peripheral portion of one adjacent tumbler and frictionally engages said tumbler and helps to hold the spacer and tumbler in a correct position relative to each other. Also each spacer 147 is internally provided with an inwardly protruding lug 155, shown at the left in Fig. 8, that projects into a groove 65 156 in the inner body member 65, the groove 156 being clearly shown in Fig. 9. Preferably the lugs 155 are integral with the spacers 147 and have their edges bent over so that said lugs are of U shape in cross section, as shown in Fig. 8. This gives the lugs greater strength and more bearing surface in the groove 156. The lugs 155 connect the spacers 147 with the inner core member 65 in such a manner that all of the spacers 147 will be rotatively moved along with the inner core member 65.

The tumblers 146 and spacers 147 are assembled between the end portion 92 at one end, and the resilient lock ring 123, at the other end, see Fig. 1, and are frictionally held under enough endwise and radial pressure so that rotary movement of the spacers 147 will move the tumblers 146 unless said tumblers are otherwise restrained from movement. Radial friction on the circumferential portions of the tumblers 146 may be provided by the overhanging flanges 154 of the spacers 147, which may be extended lengthwise of the core beyond the extension shown to completely infold and hide the tumblers 146 on the outside.

The tumblers 146 and spacers 147 are quickly and easily assembled on members 65 and 66 and are as quickly and as easily disassembled by first removing the lock ring 123 and then block 210. Thus it is easy to remove the tumblers 146 in the event the combination or combinations of the lock core are to be changed. In practice, block 210 may be dispensed with or made integral with lock ring 123.

The overhanging flange 154 of the spacers 147 extend over the peripheral portions of the tumblers 146 and shield and protect said tumblers and prevent them from coming in contact with any of the adjacent parts of the core or housing. These flanges may be extended to completely overhang and hide the exterior of said tumblers if desired.

As the bar extension 103 is required to pass downwardly over the cam surface 143 and beyond said cam, for ordinary lock operation, it is necessary to provide the clearance space 38 in the end plate 146 in order to provide clearance for end piece 212 carried on the end portion of said bar extension 103. Also when the lock control bar 109 is positioned in its outermost radial position in a set of deep notches 152 the end portion of said lock control bar will just clear the inclined surface 144 and be positioned in the clearance space 38 as the end of bar extension 103 moves beyond cam surface 143, Fig. 6.

The throw means, Figs. 1, 2, 3, 4 and 5 of this lock, is positioned between the plate member 140 and the end 41 of the housing. This throw means includes primary throw lug 83, certain gears and gear segments and secondary throw member 159 that are arranged to provide lost motion before and after the secondary lock-operating cycle, employed to unlock a secondary lock mechanism.

Key

A key for operating this core is shown in Figs. 1 and 25 and cross sections of said key are shown in Figs. 6 to 10 inclusive. This key comprises a blade 180 having the usual lobe 181 on its outer end and having a shouldered portion 182 adjacent the lobe. The portions 180 and 182 are adapted to enter the keyway 78 in the face member 63 and the shouldered portion 182 is adapted to abut against a shoulder 183 in the said face member 63 to position the key longitudinally in the core.

A notch 184 is provided in the blade 180 a short distance forwardly of the shouldered portion 182 for engagement with the previously described lug 94 on the circular end portion 92, see Figs. 11 and 24. Figs. 10 and 11 both show that this lug 94 is clear of the keyway 78 when the members 64, 65 and 66 of the core are in the position they will occupy at the time the key is inserted therein or removed therefrom. After the key has been

inserted and as soon as clockwise movement of said key is initiated it will be engaged with the lug 94 and cannot thereafter be withdrawn from the core until it is turned back into the initial or starting position.

The key blade 180 is provided with two longitudinally spaced apart notches 186 and 187 for the reception of a separable combined portion 188 herein referred to as a key bit. Overhanging portions 189 and 190 are provided in connection with the respective notches 186 and 187 to engage with lugs 191 and 192 on the respective ends of the separable key bit 188.

The bitted edge of the key bit is a series of stepped portions 206 which are longitudinally offset from each other the proper distances to cause the stepped portions of the key always to align themselves with the respective tumblers 146 when the key is in the correct lock operating position in the lock. When the tumblers 146 are moved toward the key bit 188 the shoulders 149 on the tumblers engaged with the sides of the stepped portions 206 of the key bit and the tumblers are thus positioned by the key bit.

The lugs 191 on the end of the key bit member are preferably two in number and are transversely spaced apart of a locking member 194, see Fig. 1, that is embedded in the key blade 180. The locking member 194 has two inclined portions 195 and 196 that are guided in the key blade 180 in such a manner as to cause the locking member to be moved toward the key bit 188 when it is moved toward the tip end of the key blade and to be moved away from the key bit 188 when it is moved toward the lobe end of the key.

A shallow groove 203 is provided in the bottom edge of the separable bit member 188 to receive the top edge of the locking member 194 and thereby cooperate with the locking lug 193 to lock the detachable bit member 188 against transverse displacement.

When the key is inserted in the core the pin 91 will move into the end of the key, as shown in Fig. 1, and the locking member 194 and locking lug 193 will be moved thereby out of engagement with the groove 203 and lugs 191. When this occurs the separable key bit 188 will be released as respects the key blade, and the key blade 180 and key bit 188 can be moved sidewise relative to each other. When the separable key bit 188 is locked to the key blade 180, the lugs 191 and 192 are held beneath the overhanging portions 189 and 190 of the blade, the lug 193 is positioned between the lugs 191 and the locking member 194 is positioned in the groove 203. This binds the bit member firmly and immovably to the key blade and said bit member will not be normally detached from the key blade at any time except when the key is inserted in the core and turned. Also said key bit will be re-engaged with the blade as the key is being removed from the core.

The combined portion 206 of the key bit member is narrower than the base portion thereof, as best shown in Fig. 8, to provide on the key bit member, a shoulder 207 that is adapted to be engaged by an overhanging ledge 178 of the body portion 116 of the outer body member 66. The ledge 178 cooperates with the ribs 81 to trap and hold the key bit 188 securely within the outer body member during the operation of the lock.

Operation

The core mechanism shown in Figs. 1 to 25 may be operated, so as to operate a secondary mechanism, through throw-member 159, by all keys

11

that have properly combined detachable bits and which will enter the lock core and align a set of notches, composed of either or both notches 152 and 153, entirely across the series of tumblers 146 therein. These keys may include ordinary operating keys which will operate only one lock, of a group or series of locks, or various master and sub-master keys which will operate various groups within the series, and control keys which perform the double function of operating the locks they are made to fit and of removing the primary lock mechanisms or cores of said locks from the housings.

Thus any of said keys may be made to serve as a control key.

The usual operation of this lock by an operating key will now be described:

A key of proper combination is inserted in the core in the usual manner until the stop shoulder 182 rests against the shoulder 183. For this position of the key the key bit 188 will be properly aligned with the tumblers 146 and said key bit 188 will be securely held within the portion 116 of the outer body member 66, as shown in Fig. 8, with the ledge 178 of the portion 116 being engaged over the shoulders 207 of the key bit and the ribs 81 engaging with the lower edge portion of said key bit. Also for this position of the key the pin 91, Fig. 1, will be engaged with the pin 200 in the key blade 180 and the locking member 194 in said key blade will be moved into releasing position as respects the key bit 188.

To operate the lock, after insertion of the key as described in the preceding paragraph, said key is turned in a clockwise direction. As the key begins to move clockwise the key bit and outer body member 66 will remain stationary but the inner body member 65 and spacers 147, which are connected with the inner body member 65 through the lugs 155, will be angularly moved with the key. Movement of the spacers 147 will move the several tumblers 146, which are frictionally connected with the spacers 147, until the shoulders 149 of the respective tumblers 146 engage with the stepped portions 206 of the key bit. When each tumbler 146 engages with the key bit it will be stopped and will not rotate any further until the key bit begins to move. Preferably this movement of the key bit and outer body member 66 will begin at the end of about forty degrees movement of the key. I term this forty degrees the pick-up movement as diagrammatically shown in Fig. 19.

It is during this pick-up movement that all of the tumblers 146 are properly positioned for operation of the lock, provided a key having a proper combination is being used. If a key of a wrong combination is being used it can be turned through this first forty degrees of pick-up movement and through the trial zone of operation but cannot be turned beyond the unlocking trial zone because the tumblers 146 will not be properly aligned to receive the lock control bar 109 and further operation of the lock will be prevented.

At the time the key is inserted in the lock the outer body member including the portion 116 shown in Figs. 23 and 22, will be locked to the end plate 140 by the engagement of the portion 131 of locking slide 130 in the recess 132 and by engagement of the edge 134 with the cam surface 135 and by the abutting relation of the end portion 138 of said locking slide 130 against the wall of end flange 86. As long as the outer body member 66 thus remains locked to the housing 49 it cannot be moved rotatively and the key bit 188

12

will be held in a fixed position while the tumblers 146 are moved into engagement with said key bit.

When the key handle and inner body member 65 begin to move clockwise from the initial or starting position the recess 139 in the end flange 85 begins to move toward the locking slide 130, Fig. 22. By the time the key and inner body member 65 have completed their clockwise movement through the pick-up portion of their cycle the recess 139 will be substantially in registration with the conical end portion 138 of the locking slide 130 but the position of the locking slide 130 will not have changed.

However, when the key and inner body member 65 reach the end of the pick-up movement, Fig. 19, in a clockwise direction the shoulder 128 of the inner body member 65 will contact the shoulder 118, Fig. 8, of the outer body member 66.

Thereafter, upon further movement of the key and inner body member in a clockwise direction, the outer body member will be rotatively moved therewith and the locking slide 130 will be longitudinally moved to the right, as respects the showing in Figs. 22 and 23. This releases the engagement of the locking slide 130 with the end plate 140 and moves the cone shaped end portion 138 of said locking slide 130 into the recess 139 thus locking the inner and outer body members 65 and 66, Fig. 24, together.

Also at substantially the end of the pick-up portion of the stroke, i. e., at the end of forty degrees of clockwise movement of the key and inner body member 65, the end 145 of bevelled surface piece 112 riveted to the bar extension 103, Fig. 18, will begin to move the cam surface 142 and the spring 107 will begin to move the longitudinally movable bolt member 64, Fig. 24, inwardly. This will cause the inclined ribs 112 on the portion 81, Figs. 18 and 20, to tend to move the cooperating inclined ribs 111 and the lock control bar 109 outwardly toward the notches 152 and 153 in the tumblers 146. If the key is of a proper combination and the tumblers 146 are properly positioned so that a set of the deeper notches 152 are lined up across the tumblers then the lock control bar 109, which is being urged toward the notches 152 by the spring 107 will drop into the notches 152 and operation of the lock can continue on to the end of the operating cycle, Fig. 19, and will be stopped at the end of said operating cycle.

The trial portion of the cycle during which the spring 107 is urging the lock control bar 109 into the notches 152 is preferably the succeeding twenty degrees beyond the end of the pick-up portion, see Fig. 19, and the operating portion of the cycle is the succeeding sixty degrees beyond trial portion. The usual operating keys will only turn the lock core through these three cycles but a control key will turn the lock core through a further control cycle of operation, preferably of sixty degrees and bring said core to a position where it may be removed from the housing.

Obviously the angles through which the key is turned for pick-up, trial, operating and control may be varied in the design of the lock, the angles herein described being merely illustrative of one set of angles by which this sequence of operations can be satisfactorily carried out.

When the three members 63, 64 and 65 of the core, Fig. 24, first begin to move clockwise from the starting position the stop lugs 98, 99 and 100, Figs. 13, 17 and 24, on the crescent shaped end plate 97 of bolt member 64 will be in the annular

13

path of the fixed housing lugs 48, 49 and 50, Fig. 17, but can be moved substantially sixty degrees clockwise, see Fig. 13, before they are stopped by the lugs 48, 49 and 50. This makes it possible to operate the lock mechanism through the pick-up and trial portions of the cycle with any key of the type disclosed that can be inserted therein even though the key bit is not cut to the right combination.

However, for the lock to be operated beyond the end of the trial position it is necessary that the bolt member 64, which carries the lugs 98, 99 and 100, should be moved endwise, to the left as respect the showing in Figs. 1 and 17, far enough so that the lugs 98, 99 and 100 will be clear of the lugs 48, 49 and 50. The lugs 98, 99 and 100 must be thus in the clear by the time the lock parts have reached the end of the trial position in their clockwise movement.

Also it is necessary that the lugs 98, 99 and 100 should be moved to the left, Fig. 17, without interfering with the housing lugs 51 to 56 inclusive until the end of the operating stroke, at which time the lugs 98, 99 and 100 are in contact with, and stopped by, the three lugs 54, 56 and 52 respectively.

This movement to the left, as respects the showing in Figs. 1 and 17, of the lugs 98, 99 and 100 of bolt member 64 is controlled by three co-operating elements. These elements are, the lock control bar 109, the inclined cam surfaces 142 and 143 and adjacent surfaces of end plate 140, and the spring 107.

The lock control bar 109 must find the notches 152 or notches 153 or a combination of notches 152 and 153 of the tumbler rings properly aligned before it can be moved into said notches by the spring 107. The inclined cam surfaces 142 and 143 and adjacent surfaces of end plate 140 must control endwise movement of the bar extension 103 and the bolt member 64 and lugs 98, 99 and 100 carried thereby, in such a manner that the lugs 98, 99 and 100 will clear the lugs 48, 49 and 50, and will not interfere with the housing lugs 51 to 56 inclusive until the operation of the lock is completed. If the lock control bar 109 has dropped only into properly aligned deep notches 152 in the tumblers, the lugs 98, 99 and 100 will clear the lugs 48, 49 and 50 and will then be guided past certain of the lugs 51 to 56 inclusive, after which the end piece 212 and bar extension 103 will ride over the inclined cam surface 143 and the lugs 98, 99 and 100 will move into the angular path of the lugs 51 to 56 inclusive and will be stopped by lugs 54, 56 and 52 at the end of the operating period of the cycle.

The dotted lines in Fig. 17 illustrate the paths of movement of the lugs 98, 99 and 100 in bypassing some of the housing lugs 51 to 56 inclusive. For instance, the lug 98 first moves in a straight line until it is substantially alongside of the lug 70. Then, as the inclined cam surface 142 at the end of the bar extension 103, Fig. 18, allows the bar extension 103 and bolt member 64, Fig. 24, to move to the left, this lug 98 moves angularly, clockwise and to the left, Fig. 17, until it is in the pathway between the set of lugs 48 to 50 and the set of lugs 51 to 56. Then said lug moves clockwise, as end piece 212 and the bar extension 103 rides on the flat surface of end plate 140, until it has by-passed lug 53. Then, as end piece 212 and the end of the bar extension 103 rides down over the inclined cam surface 143, this lug 98 moves angularly, clockwise and to the left, the same being downwardly in Fig. 17,

14

into line with the lug 54 and comes to a stop against the lug 54 at the end of a key movement of one hundred twenty degrees.

In a similar manner the lugs 99 and 100 move simultaneously with the lug 98 to by-pass the respective lugs 55 and 56 and come to a stop against the lugs 56 and 52 respectively.

In a counterclockwise or return movement of the key and core mechanism the inclined cam surfaces 143 and 142 will cause the lugs 98, 99 and 100 to follow, in a counterclockwise or reverse direction, the paths just previously described back to the starting position.

Thus in the normal operation of the lock for the purpose of retracting a secondary mechanism a properly bitted operating key is inserted, with the bit uppermost. This key is then turned through an angle of substantially one hundred twenty degrees to first properly align the tumblers and position the lock control bar 109 in the tumbler notches and then to impart a turning movement of substantially ninety degrees to the throw member 159 which protrudes from the end of the lock housing. Thus the sixty degree operating movement of the key produces a ninety degree movement of the throw member 159.

In the pick-up movement of an ordinary operating key, Fig. 19, the key bit 188 will remain stationary and the tumblers 146 will be frictionally moved into engagement with said key bit and a set of deeper notches 152 will be lined up with lock control bar 109 entirely across the set of tumblers.

Upon further clockwise movement of the operating key through the trial portion of its cycle the lock control bar 109 will be moved into the aligned notches 152 thus allowing the movable lugs 98, 99 and 100 to clear the respective housing lugs 49, 50 and 48 so that clockwise movement of the key may be continued through the operating portion of the cycle.

During movement through the operating portion of the cycle the end piece 212 of bar extension 103 will pass over the inclined cam surface 143 and rotation will be stopped at the end of the operating cycle by engagement of the lugs 98, 99 and 100 with the housing lugs 54, 56 and 52.

At the time the key begins to move clockwise from the starting position the interrupted gear member 171-172 of the throw mechanism will simultaneously begin to move clockwise from the position shown in Figs. 3 and 4. In the starting position the long teeth 169 of the gear segments 165 are resting on the circumferential portion of the gear member 172 and the end of one shorter tooth 170 of each gear segment 165 is pointed toward the center of interrupted gear member 171 and positioned so that it will move along one of the smooth peripheral surfaces 175 of said interrupted gear member 171.

During clockwise movement of the key through the pick-up and trial portion of its cycle the interrupted gear member 171-172 will move rotatively without turning the gear segments 165 on their axes. At substantially the time the key reaches the end of the trial portion of its movement a short tooth 170 of each gear segment 165 will be engaged by a tooth 174 of the gear member 171 and the gear segments 165 will begin to move rotatively, the long teeth 169 entering the recesses 177 and 178, see Figs. 4 and 3.

These gear segments 165, as illustrated, preferably will be rotated through an angle of substantially ninety degrees while the key and gear member 171-172 are moving clockwise through

the sixty degree operating portion of the cycle. The recesses 177 and 178 receive the longer teeth 169 as the gear segments 165 rotate. At the end of about ninety degrees of rotary movement of the gear segments 165 the long tooth 169 of each gear segment 165 will again rest on a peripheral portion of the gear member 172 and will prevent further rotary movement of the gear segments 165 in the event the key is turned beyond the end of the operating portion of the cycle. The only key that can and will be turned beyond the end of the operating portion of the cycle is a control key when it is being used for the removal of the core from the housing, as described in my co-pending application Serial No. 572,907.

Rotation of the gear segments 165 is transmitted directly to the gear segments 161 which, in the present instance, act through the gear member 160 to rotatively move the throw member 159 through the same angle as the gear segments 165 and 161 but in the opposite direction.

From the above described operation of the throw mechanism it will be apparent that said throw mechanism provides sufficient lost motion at the beginning of the cycle of operation of the key to prevent turning of the throw member 159 while the key and parts of the lock mechanism are being moved through the pick-up and trial portions of their cycle. Also it will be apparent that this throw mechanism will transmit substantially ninety degrees of rotary movement to the throw member 159 while the key and core are moving through substantially sixty degrees of the operating portion of the cycle. Also it will be apparent that this throw mechanism is capable of providing for substantially sixty degrees of lost motion beyond the end of the operating portion of the cycle in the event the lock core is to be removed from the housing. Obviously other desired gear ratios between the key operated throw member 67 and the throw member 159 and degrees of lazy motion both before and after the operating cycle can be obtained by varying the relative sizes of the gear members 161 and 160 and related parts.

This throw mechanism is further adapted to provide corresponding inverse lost motion and rotary motion of the several parts of the throw mechanism as a key in the lock is rotatively moved in a counterclockwise direction from the end of the operating or control position back to the starting position.

In many types of locks the throw mechanism herein disclosed is enlarged and changed in many ways. For instance the hub of one of the gear segments 161 may be made the main throw member in the secondary lock mechanism in case it is desirable that the throw member be off center as respects the lock housing. Such a set-up is disclosed in U. S. Letters Patent No. 2,138,856, issued December 6, 1938.

When this structure is used the throw pin is aligned on the axis of the core and any forcible rotating of core and housing could not unlock the secondary lock.

Any desired degree of masterkeying and sub-masterkeying may be provided in this core by the use of more than one of the deeper notches in any desired number of the tumblers. In the lock shown in Figs. 1 to 24 one billion different combinations are possible.

Having thus described my invention, what I claim as new and desire to protect by Letters Patent of the United States of America is:

1. In a lock core, consisting of a key-operable

primary lock mechanism adapted to complement a secondary lock mechanism, the combination of elements comprising a face member, an inner body member and a throw member, integrally joined to form a core frame, a keyway in said core frame, said core frame having a portion adapted to receive a number of ring tumblers and means adapted to releasably retain said ring tumblers thereon, said ring tumblers being adapted to cooperate with key means in said keyway to control operation of said primary lock mechanism.

2. In a lock core, consisting of a key-operable primary lock mechanism adapted to complement a secondary lock mechanism, the combination of

elements comprising a face member, an inner body member and a throw member, integrally joined to form a core frame, a keyway in said core frame, an outer body member carried by said core frame, said outer body member and said core frame jointly providing a round portion adapted to receive a number of ring tumblers thereon, and means adapted to releasably retain said ring tumblers thereon, said ring tumblers being adapted to cooperate with key means in said keyway to control operation of said primary lock mechanism.

3. In a lock core, consisting of a key-operable primary lock mechanism adapted to complement a secondary lock mechanism, the combination of

elements comprising a face member, an inner body member and a throw member integrally joined to form a core frame, a keyway in said core frame, an outer body member carried by said core frame forming an extension of the said keyway

in said core frame, said outer body member and said core frame jointly providing a portion adapted to receive a number of ring-shaped tumblers thereon, and means adapted to releasably retain said ring tumblers thereon, said ring-

like tumblers being adapted to cooperate with key means in said keyway and said extension thereof to control operation of said primary lock mechanism.

4. In a lock core, consisting of a key-operable

primary lock mechanism adapted to complement a secondary lock mechanism, the combination of

elements comprising a face member, an inner body member and a throw member, integrally joined to form a core frame, a keyway in said

core frame, an outer body member carried on said core frame adjusted to a limited rotary movement relative to said core frame, said outer body member forming an extension of said keyway in said core frame, said outer body member and said

core frame jointly providing a portion adapted to receive a number of ring-shaped tumblers thereon, and means adapted to releasably retain said ring tumblers thereon, said ring-like tumblers being adapted to cooperate with a key blade in

said core frame and a separable key bit in said extension of said keyway in said outer body member to control operation of said primary lock mechanism.

5. In a lock core, consisting of a key-operable

primary lock mechanism adapted to complement a secondary lock mechanism, the combination of

elements comprising a face member, an inner body member and a throw member, integrally joined to form a core frame, a keyway in said

core frame, an outer body member carried on said core frame adjusted to a limited rotary movement relative to said core frame, said outer body member forming an extension of said keyway in said core frame, said outer body member

and said core frame jointly providing a round

portion adapted to receive a number of ring-shaped tumblers thereon, means adapted to releasably retain said tumblers thereon, said tumblers being adapted to cooperate with a key blade in said core frame and a separable key bit in said extension of said keyway in said outer body member to control operation of said primary lock mechanism, and means adapted to separate the said key bit from the key blade and reunite said key bit into said key blade by moving said core frame relative to said outer body member in the operation of said primary lock mechanism.

6. In a lock core, consisting of a key-operable primary lock mechanism adapted to complement a secondary lock mechanism, the combination of elements comprising a face member, an inner body member and a throw member, integrally joined to form a rigid core frame, an outer body member mounted on said inner body member and adapted to limited rotary movement relative thereto, and a locking slide carried by said outer body member adapted to control the relative movement of the outer body member relative to the inner body member.

7. In a lock core, consisting of a key-operable primary lock mechanism adapted to complement a secondary lock mechanism, the combination of elements comprising a face member, an inner body member and a throw member, integrally joined to form a rigid core frame, an outer body member carried on said core frame, and a locking slide mounted in said outer body member and adapted to selectively lock said outer body member to said secondary lock mechanism and to said core frame.

8. In a lock core, consisting of a key-operable primary lock mechanism adapted to complement a secondary lock mechanism, the combination of elements comprising a face member, an inner body member and a throw member, integrally joined to form a rigid core frame, an outer body member mounted on said inner body member, said outer body member being trapped against endwise motion and limited in its rotative motion on said inner body member, and a locking slide carried by said outer body member adapted to selectively lock said outer body member to said inner body member and to a part of said secondary lock mechanism.

9. In a lock core, consisting of a key-operable primary lock mechanism adapted to complement a secondary lock mechanism, the combination of elements comprising a face member, an inner body member and a throw member, integrally joined to form an integral core frame, an outer body member carried by said inner body member, said outer body member being trapped against endwise motion and limited in its rotative motion on said inner body member, and a locking slide carried by said outer body member adapted to lock said outer body member to said secondary lock mechanism during one portion of the cycle of operation of said primary lock mechanism and to lock said outer body member to said core frame during another portion of the cycle of operation of said primary lock mechanism.

10. In a lock core, consisting of a key-operable primary lock mechanism adapted to complement a secondary lock mechanism, the combination of elements comprising a face member, an inner body member and a throw member, integrally joined to form a rigid core frame, a keyway in said core frame, an outer body member, having an extension of said keyway, carried by said core frame, and key-operable means adapted to dis-

assemble and assemble a key bit from and into a key blade, respectively, in the operation of the said primary lock mechanism.

11. In a lock core, consisting of a key-operable primary lock mechanism adapted to complement a secondary lock mechanism, the combination of elements comprising a face member, an inner body member and a throw member, integrally joined to form a rigid core frame, a keyway in said core frame, an outer body member, having an extension of said keyway, carried by said core frame, and key-operable means adapted to disassemble a separable key bit, occupying the said keyway extension in said outer body member, from a key blade occupying the said keyway in said core frame, at the beginning of the unlocking movement of the said primary lock mechanism.

12. In a lock core, consisting of a key-operable primary lock mechanism adapted to complement a secondary lock mechanism, the combination of elements comprising a face member, an inner body member and a throw member, integrally joined to form a rigid core frame, a keyway in said core frame, an outer body member, having an extension of said keyway, carried by said core frame, and key-operable means adapted to assemble a separable key bit, occupying the said keyway extension in said outer body member, into a key blade occupying the said keyway in said core frame, at the end of the locking movement of the said primary lock mechanism.

13. In a lock core, consisting of a key-operable primary lock mechanism adapted to complement a secondary lock mechanism, the combination of elements comprising a face member, an inner body member and a throw member, integrally joined to form a rigid core frame, a keyway in said core frame, and a bolt member carried by said core frame and adapted to limit the rotative movements of the said core within the said secondary lock mechanism.

14. In a lock core, consisting of a key-operable primary lock mechanism adapted to complement a secondary lock mechanism, the combination of elements comprising a face member, an inner body member and a throw member, integrally joined to form a rigid core frame, a keyway in said core frame, a bolt member carried by said core frame and adapted to limit the rotative movement of the said core, relative to said secondary lock mechanism, and lock control bar means, carried by said bolt means, adapted to control said bolt member.

15. In a lock core, consisting of a key-operable primary lock mechanism adapted to complement a secondary lock mechanism, the combination of elements comprising a face member, an inner body member and a throw member, integrally joined to form a rigid core frame, a keyway in said core frame, a bolt member, carried in said core frame controlling the rotary movement of said core in said secondary lock mechanism, lock control bar means, substantially as set forth, carried by said bolt member and controlling the movements of said bolt member, and ring tumbler means enveloping said inner body member, said bolt member and said lock control bar means, all built into a cylindrical form and all adapted to function as disclosed.

16. In a lock core, consisting of a key-operable primary lock mechanism adapted to complement a secondary lock mechanism, the combination of elements comprising a face member, an inner body member and a throw member, integrally

joined to form a rigid core frame, a keyway in said core frame, and a tumbler-receiving portion of said core frame adapted to be telescoped within a stack of ring tumblers separated by ring spacers and releasably secured in place on said core frame by snap ring means, all adapted to form a cylindrical lock core.

17. In a lock core, consisting of a key-operated primary lock mechanism adapted to complement a secondary lock mechanism, the combination of elements comprising a face member, an inner body member and a throw member, integrally joined to form a rigid core frame, a keyway longitudinal of said core frame, said inner body member being adapted to be telescoped within a stack of ring tumblers separated by ring spacers, said tumblers and spacers being releasably secured on said inner body member by snap ring means, said spacers having inwardly extending lugs that are engaged in a longitudinal groove along the said inner body member.

18. In a lock core, consisting of a key-operable primary lock mechanism adapted to complement a secondary lock mechanism, the combination of elements comprising a face member, an inner body member and a throw member, integrally joined to form a rigid core frame, a keyway in said core frame, and a row of outwardly extending lugs round about said face member adapted to engage inwardly extending lugs within the said secondary lock mechanism to releasably retain said lock core in said secondary lock mechanism.

19. In a lock core, consisting of a key-operable primary lock mechanism adapted to complement a secondary lock mechanism, the combination of elements comprising a face member, an inner body member and a throw member, integrally joined to form a rigid core frame, a bolt member within the core frame adapted to slight motion endwise of the core, and a plurality of pins on said bolt member extending endwise of the lock core and fitting corresponding holes in the face member to prevent independent rotary movement of the said bolt member relative to the said core frame.

20. In a lock core, consisting of a key-operated primary lock mechanism adapted to complement a secondary lock mechanism, the combination of elements comprising a face member, an inner body member and a throw member, integrally joined to form a rigid core frame, a bolt member within the core frame adapted to slight motion endwise of the core therein, a plurality of pins on said bolt member extending endwise of the lock core and fitting corresponding holes in the face member to prevent independent rotary movement of the said bolt member relative to the said core frame, and lugs on said bolt member adapted to engage lugs within said secondary lock mechanism to limit the rotary movement of the said lock core relative to said secondary lock mechanism.

21. In a lock core adapted to complement a secondary lock mechanism, the combination of 65 elements comprising a face member, a body member and a throw member, said face member

having a substantially cylindrical form and an annular row of lugs adapted to cooperate with an annular row of lugs in a cylindrical core receptacle of said secondary lock mechanism, to releasably retain said core in said core receptacle, substantially as set forth.

22. In a lock core adapted to complement a secondary lock mechanism, the combination of elements comprising a face member, a body member, a bolt member and a throw member, said face member and said body member forming an integral unit adapted to carry said bolt member thereon said bolt member being prevented from independent rotary movement relative to said face and body members but adapted to limited endwise movement relative to said face and body members, said bolt member having an annular row of lugs adapted to cooperate with annular rows of lugs in said secondary lock mechanism to limit the rotative movement of said core in said secondary lock mechanism.

23. In a lock core adapted to complement a secondary lock mechanism, the combination of elements comprising a face member, body member, a bolt member and a throw member, said face and body members forming an integral unit adapted to carry said bolt member thereon, said face member having a cylindrical form and an annular row of lugs adapted to cooperate with an annular row of lugs in a cylindrical core receptacle of said secondary lock mechanism, to releasably retain said core in said secondary mechanism, said bolt member being locked against independent rotary motion relative to said face and body members but adapted to limited endwise movement relative to said face and body members, said bolt member having an annular row of lugs adapted to cooperate with annular rows of lugs in said secondary lock mechanism to limit the rotative movement of said core in said secondary lock mechanism.

24. In a lock core, two relatively telescopic core members, a plurality of ring tumblers rotatively supported on said two core members, a readily removable resilient snap ring means securing said tumblers and said core members in assembled relation providing frictional engagement between said tumblers and said core members.

25. In a lock core, two relatively rotatable lock core members, and resilient snap ring means extending around said two relatively rotatable lock core members and frictionally connecting said two relatively rotatable lock core members as respects relative rotation.
